ROBERT S. BOLGER, OF NEW YORK, N. Y., ASSIGNOR TO INTERNATIONAL MOTOR COMPANY, OF NEW YORK, N. Y., A CORPORATION OF DELAWARE.

COOLING SYSTEM FOR MOTOR FIRE-ENGINES.

1,335,552.

Specification of Letters Patent. Patented Mar. 30, 1920.

Application filed June 24, 1919. Serial No. 306,390.

To all whom it may concern:

Be it known that I, ROBERT S. BOLGER, a citizen of the United States, whose residence and post-office address is Richmond Hill, in the borough of Queens of the city of New York, in the State of New York, have invented certain new and useful Improvements in Cooling Systems for Motor Fire-Engines, of which the following is a specification, reference being had to the accompanying drawing, forming a part hereof.

In motor propelled fire engines the discharge, for a motor of given rating, is dependent upon the horse power delivered at the pump. Accordingly, it is desirable when the motor is employed for driving the fire pump, that all unnecessary loss of power through the diversion of some of the motor power to its associated elements, be reduced to a minimum. It is the principal object of this invention to save the power usually employed in driving the water pump of the circulating system for the motor by rendering this pump inoperative during the use of the fire pump, in the sense that the water pump for the circulating system is not relied upon to force the cooling water through the jackets of the motor. A further object of the invention is to cool the motor by water taken from the fire hose during the use of the fire pump so that when the motor is under its heaviest duty it will be cooled constantly by water at about the temperature of the main.

The invention will be described in one embodiment in a motor fire engine in connection with the accompanying drawing in which—

Figure 1 is a view in side elevation of so much of a motor fire engine as is necessary for an understanding of the application of the improved cooling system thereto.

Fig. 2 is a view on a larger scale of the motor fire engine shown in Fig. 1, the hood and dash being removed in the interest of clearness.

The truck *a* carries, as usual, a propelling internal combustion engine *b*, the cooling circulatory system of which includes a water pump *c* connected through a hose *d* with the water jackets *b'* of the motor and a return connection to the pump indicated as a hose *e*. From the water jackets the water is led through a pipe connection *b*² to a water reservoir *f* which, in turn, is connected, to the return pipe *e* of the pump *c* and is pro-

vided with an overflow pipe *f'*, as is usual. In accordance with the present invention the fire pump indicated generally at *g* is connected preferably, on its outlet side *g'* through a pipe *h* to some point of the water circulatory system, such as the pipe *d* leading to the cylinder jackets. On the other side of the fire pump *g*, as at the inlet *g*², there is a pipe connection *i* to another portion of the water circulatory system, such as the overflow pipe *f'*. It is ordinarily desirable, owing to the relatively high water pressures in the pipes *g'* *g*² of the fire pump to include in the connecting pipes *h*, *i*, suitable pressure and vacuum regulators *h'*, *i'*, respectively. In the particular embodiment of the apparatus illustrated, it will be evident that the water flowing from the outlet *g'* into the pipe *h* will be under a pressure and water returning to the inlet side *g*² through the pipe *i* will be subjected to a negative pressure. The rate of flow through these pipes, accordingly, can well be controlled by the pressure and vacuum regulators *h'*, *i'* referred to.

When the fire pump *g* is not in use, as during the propulsion of the truck *a*, the improved cooling system may be cut off from the usual circulatory system by closing suitable valves *h*², *i*² located within the connecting pipes *h*, *i* respectively. At this time the pump *c* will be connected to the circulatory system through a valve *d'*, conveniently located within the connecting pipe *d*, such a valve being desirable for reasons which will appear, although it is to be understood that this valve may be omitted and the benefits of the invention realized to a very substantial extent. When the motor *b* is in normal use any excess of water in the reservoir *f* may drip from the pipe *f'* past an opened valve *f*² which may be located at the lower end thereof. When the fire pump *g* is in operation, it will be desirable to render the water pump *c* for the cooling system inoperative in the sense that no appreciable power from the motor is required to drive it, so that the power ordinarily thus consumed may be delivered to the fire pump in form for useful work. Further, by cutting the pump *c* out of the system while the fire pump *g* is in use, it becomes possible to deliver fresh water constantly from the pump through the circulatory system at a time when the motor is under heaviest duty. To

bring the improved system into operation, the valves h^2 , i^2 are opened and the valve f^2 in the overflow pipe f' is closed. At this time some water is taken from the outlet 5 side g' of the pump g and delivered to the cooling system of the motor through the pipe h passing from the motor into the reservoir f and returning to the inlet side g^2 of the pump through the pipes f' , i . The pressure 10 sure regulator h' and vacuum regulator i' will so control the rate of flow of the water through the circulatory system as to insure a steady flow therethrough of such volume as is best adapted for the capacity of the 15 circulating system. With the parts in the conditions described it is evident that the water pump c will merely idle. The power ordinarily employed to drive the pump c is thereby saved to the motor and consequently 20 delivered to the pump g in form for useful work. This condition may possibly be bettered by closing off the pipe d from the pump c , as by means of the valve d' , in which case the pump c not only idles but is 25 protected from any counter pressure which might be set up by the water flowing in through the pipe h .

It is to be understood that the invention is not to be limited to the precise embodiment 30 illustrated nor to the arrangement of the pipes and valves described since it is evident that the advantages might be realized in other constructions which will produce the desired results. For instance, the pipe connections h , i , might be reversed and the inflowing and outflowing water connections 35 might be had at other parts of the system than those shown.

The scope of the invention is defined by 40 the accompanying claims.

I claim as my invention:

1. In motor fire engines, in combination with the motor and cooling system therefor, a fire pump, inflow and return connections 45 from the opposite sides of the pump to the cooling system to impress positive and negative pressures on the inlet and outlet, respectively, of the cooling system and means to cut off said connections from the cooling 50 system.

2. In motor fire engines, in combination with the motor and cooling system therefor, a fire pump, inflow and return connections from opposite sides of the pump to the cooling system, devices in said connections for regulating the rate of flow and means to cut off said connections from the cooling system. 55

3. In motor fire engines, in combination with the motor and cooling system therefor, a fire pump, inflow and return connections from the pump to the cooling system on the outlet and inlet sides thereof, respectively, pressure and vacuum regulating devices in the inflow and return connections, respectively, and means to cut off said connections from the cooling system. 60

4. In motor fire engines, in combination with the motor and cooling system therefor, a fire pump, a water circulatory pump in 70 the cooling system, a connection from the fire pump to the cooling system at a point between the circulatory pump and the motor, a water reservoir in the system, a return connection therefrom to the circulatory 75 pump, a return connection from the reservoir to the fire pump and means to cut off the connections from the fire pump.

5. In motor fire engines, in combination with the motor and cooling system therefor, a fire pump, a water circulatory pump, a connection from the last named pump to the motor, a connection from the fire pump to the last named connection, a valve between the water circulatory pump and the 80 point of connection of the fire pump to the circulatory system, a water reservoir in the system, a return connection therefrom to the circulatory pump, an overflow pipe for the reservoir, a return connection from the fire 85 pump to the overflow pipe, a valve to close the overflow pipe at a point beyond its connection with the fire pump, valves to cut off the connections between the fire pump and the circulatory system and devices for 90 regulating the flow of water from the fire pump to the circulatory system. 95

This specification signed this 21st day of June, A. D., 1919.

ROBERT S. BOLGER.
